STOCK CONSISTENCY RESPONSIVE DEVICE

Hervey G. Cram, Appleton, Wis., assignor to
Manitowoc Shipbuilding Company, Manitowoc,
Wis.

Application March 30, 1944, Serial No. 528,670

7 Claims. (Cl. 73—63)

1

This invention appertains to means responsive to the consistency of pulp or stock for use in the making of paper or similar fibrous products and more particularly to an apparatus responsive to low consistency pulp or paper stock in liquid suspension ranging from .05% to 1% bone dry content and is an improvement over the Van de Carr Patent #1,665,425, issued April 10, 1928.

One of the primary objects of my present invention is to provide a consistency responsive device for use in converting any required amount of unregulated pulp or paper stock to a predetermined consistency.

Another salient object of my invention is the provision of novel means for arranging a consistency responsive device in a sample line leading from the screen head box in such a manner that it will respond to any variation in the desired consistency of the pulp or stock will be immediately reflected on the control for the gate of the unregulated stock, so that more or less stock, as the case may be, will be delivered to the white water pump without any appreciable time lag.

A further important object of my invention is the provision of a consistency responsive device embodying a housing for receiving the pulp or stock from the sample line having a rotary reticulated or perforated cylinder in said housing and immersed in the pulp or stock, with means for receiving the pulp or stock from the housing and the filtrate from the interior of the cylinder, the rate of flow of filtrate through the perforated shell of the cylinder and the pulp mass accumulating thereon depending on the consistency or thickness of the stock.

With these and other objects in view, the invention consists in the novel construction, arrangement and formation of parts, as will be hereinafter more specifically described, claimed, and illustrated in the accompanying drawings, in which drawings:

Figure 1 is an enlarged, front, elevational view of my novel consistency responsive device showing the same positioned in the sample line leading from the screen head box, parts of the view being shown broken away and in section to illustrate structural detail.

Figure 2 is a vertical, sectional view taken substantially on the line 3—3 of Figure 2 looking in the direction of the arrows, illustrating my novel consistency responsive device.

Figure 3 is an enlarged, detail, sectional view through the control float, float chamber and pilot valve used in connection with my apparatus.

2

Referring to the drawings in detail, wherein similar reference characters designate corresponding parts throughout the several views, the letter R generally indicates my novel consistency responsive device located in a sample line 5 leading from the screen head box 6 which supplies consistency regulated pulp to the screens of a paper or other machine.

As illustrated, the sample line 5 leads from 10 the bottom of the head box 6 and the inlet for the sample line is inclosed in an open ended housing 8. The open end of the housing 8 is covered by a knot screen 9 so that knots will not be delivered from the head box to the consistency responsive device.

The consistency responsive device includes a cylindrical casing 30 having a substantially circular outer wall 31 and side walls 32 and 33. Each of these side walls can be provided respectively with removable end discs 34 and 35. The end disc 35 is provided with an inwardly extending annular flange 36 which is adapted to abut one end of a centrally disposed consistency responsive device cylinder 37. This cylinder includes hub plates 38 and a cylindrical outer shell 39. The shell can be formed from reticulated material, or as illustrated, can be in the nature of a perforated drum. The hub disc 38 can be provided with openings 40 and the axial centers 20 of the hub discs are keyed or otherwise secured to an axial shaft 41. This shaft 41 is rotatably mounted in suitable bearings 42 carried by the end wall discs 34 and 35. The cylinder 37 can be rotated from a motor 43 mounted on brackets 44 carried by the casing or housing 30. As is clearly shown in Figure 2, the upper section 45 of the sample line pipe 5 communicates with the upper end of the housing or casing 30 while the lower section 46 of the line pipe 5 communicates with the lower end of the housing or casing. Between the inlet and outlet of the housing is arranged a transversely extending opening 47 for the discharge of filtrate and this opening receives 30 the filtrate chamber 48. The filtrate chamber 48 is provided with a flange 49 adjacent to its outer end and this flange is firmly secured to the walls of the opening 47 and closes said opening. The chamber 48 is the same width as the cylinder 45 and extends entirely across the cylinder and has its inner end shaped to conform to the contour of the cylinder, so that the chamber can be placed in close proximity to the cylinder. The upper edge of the chamber has secured thereto 50 a flexible blade or doctor 50 for engaging against

55 the inner end of the cylinder.

the periphery of the cylinder, whereby to wipe off the pulp adhering to the cylinder.

Communicating with the outer end of the chamber is a filtrate discharge pipe 51 and this pipe communicates with the section 46 of the sample line pipe 5. A by pass pipe 52 communicates with the housing through the end disc 35 and this communication is disposed within the flange 36 carried by said end disc. The lower end of the by pass pipe 52 communicates with the filtrate discharge pipe 51 and serves as an additional means for carrying filtrate from the cylinder, should the chamber 48 prove inadequate for this purpose.

Still referring to Figure 2, it can be seen that a fixed orifice 53 is arranged in the section 46 of the sample line pipe 5 just below the consistency responsive device housing and above the connection of the filtrate discharge pipe 51 with said section. This orifice can be formed in a plate 54 bolted between parts of the sample line pipe. The section 45 of the sample line pipe between the consistency responsive device and the screen head box 6 can be provided with a hand operated valve 55.

Leading off from the housing of the consistency responsive device above the cylinder 37 is a pipe 56 which communicates with the lower end of a float chamber 57. The float chamber 57 has mounted therein a float 58 which moves up and down with the level of the pulp in said float chamber. The float is guided in its movement by a guide rod 59. The float opens and closes a pilot valve 60 in a water pressure line 61. The pilot valve 60 includes a valve body 62 mounted on a valve stem 63 connected with the float. The valve body moves toward and away from a valve seat 64 carried by the valve casing 65. The water pressure pipe 61 communicates with the valve casing on one side of the valve seat and when the valve body moves off of the seat, water from the pressure line 61 flows into the float valve chamber.

A water over-flow conduit pipe 66 communicates with the float chamber 57 at the desired level, and acts as means for preventing the rising of the water in the float chamber above an undesired level.

Leading off from the pressure line 61 between the float chamber 57 and the pressure regulator 67 is a water conduit pipe 69 and this pipe leads to the lower end of a regulator cylinder 70 supported by the pulp regulator box 10. Mounted in the control cylinder 70 is a piston 71. Connected to the piston 71 is a piston rod 72 which leads out of the cylinder 70 and the piston rod is pivotally connected to a crank lever 73. The crank lever 73 is keyed or otherwise secured to a rock shaft 74 mounted on the regulator box. Also fixed to the rock shaft is the control gate 75 for the unregulated pulp and this gate opens and closes the opening 14 and controls the amount of pulp flowing through said opening. Normally, the flow of pulp through the opening tends to move the gate 75 to an open position and as pressure increases in the cylinder 70 below the piston, the piston will be moved upwardly to move the gate toward the opening 14.

It can be seen that as the cylinder 37 of the regulator R revolves in the mass of pulp in liquid suspension in the housing of the regulator, a mass of pulp will continuously accumulate on the perforated shell 39 thereof relative to the thickness or density of the consistency of the pulp in liquid suspension in the surrounding body. Thus

the rate of flow of filtrate through the perforated shell of the cylinder and the pulp mass accumulating thereon is inversely proportional to the thickness or density of the accumulation thereon. With a constant rate of volume flow of the sample preferably maintained by the valve 55 and by a constant head in the box 6 passing through the cylinder housing maintained by a head on the inlet side of the housing and the fixed orifice 53 at the outlet side of the housing, filtrate passed through the perforated cylinder shell and discharged by the chamber 48 and the filtrate discharge pipe 51 to the downstream side of the fixed orifice will effect the head in the section 45 of the sample line pipe 5 in direct relation to the consistency of the passing sample. By connecting this head variation on the cylinder to the float chamber 57, the float 58 will raise and lower with said head variation and the valve body 62 will move toward or away from its seat causing a change in pressure in the water pressure line 69 and this variation in pressure in the line will cause the opening and closing of the gate 75. Actually, by interconnecting the head variation on the cylinder 37, through mechanical means, to the gate 75 controlling the rate of volume flow of the parent stream of pulp, the rate of flow will be made to vary in inverse relation to consistency, and the actual rate of flow of solids will be constant.

The apparatus operates as follows: A continuous sample is delivered from the screen head box 6 through adjustable orifice or valve 55 at a sufficient rate of volume flow to establish a head 35 in the sample line pipe 5 at the level of the float 58 in the float chamber 57.

The cylinder 37 being completely submerged in the sample stream accumulates a mat of pulp on its periphery. This mat of pulp varies in thickness in direct relation to the consistency of the pulp in the sample stream.

The rate of flow of filtrate through the cylinder face is inversely proportional to the thickness of the mat of pulp through which it has to pass.

The filtrate from the cylinder 37 being discharged to the downstream side of the fixed discharge orifice 53, the rate of flow of filtrate passed through the cylinder and by passing the discharge orifice 53 determines the rate of flow through the fixed discharge orifice 53 and the head on the float 58.

An increase in the consistency of the sample effects an increase in the head which lifts the float 58 and the valve body 62 of the pilot valve 60. This increases the pressure in the pipe 69 to the cylinder 70, causing the raising of the piston 71. The piston, in turn, causes a relative closing of the gate 75 and reduction in the volume flow of unregulated stock to the intake 60 of the white water pump 23. This reduces the consistency in the stock delivered to the screen head box 6.

A decrease in the consistency effects a decrease in the head and a consequent decrease in pressure in the gate cylinder 70. This allows a relative opening of the gate 75 and an increased flow of unregulated stock to the intake of the white water pump 23 and an increase in the consistency of the stock delivered to the screens 7.

As the lapsed time is usually less than twelve seconds between the control gate 75 in the regulator box 10 and the delivery of the sample, and the reaction by the regulator, a continuous recheck and adjustment, if necessary, of the con-

sistency of the stock delivered to the screens 1 is on approximately a twelve second basis.

The regulator box 10 being located at a higher elevation than any possible level of white water in the white water chest 25, the rate of flow of pulp from the regulator box 10 to the intake of the white water pump 23 is automatically reinforced with white water from the chest 25 to make up the volume flow to the screen head box 6 as determined by the adjustment of the volume control valve 29.

Any required change in consistency is accomplished by means of the adjustable orifice or valve 55. Hence, to increase consistency, the valve 55 is adjusted toward a closed position and to decrease consistency, the valve is adjusted toward an open position.

Changes in details may be made without departing from the spirit or the scope of my invention, but what I claim as new is:

1. A consistency responsive apparatus for stock or pulp, comprising a source of stock at a constant head, a body having an inlet opening for stock communicating with said source and a discharge opening for stock, the size of said openings being fixed, a continuously rotating cylinder immersed in the stock in the body and having its periphery provided with means for the passage of filtrate therethrough and the collection of solid matter thereon at a rate depending on the consistency of the stock, the level of the body of stock surrounding the cylinder being proportional to the consistency of the stock and means snugly engaging the periphery of the cylinder for receiving the filtrate therefrom.

2. A consistency responsive apparatus for stock or pulp, comprising a body having an inlet opening for stock and a discharge opening for stock, the size of said openings being fixed, a continuously rotating cylinder immersed in the stock in the body and having its periphery provided with means for the passage of filtrate therethrough and the collection of solid matter thereon at a rate depending on the consistency of the stock the level of the body of stock surrounding the cylinder being proportional to the consistency of the stock, means snugly engaging the periphery of the cylinder for receiving the filtrate therefrom, and means for regulating the flow of stock to provide a constant feed of stock into the body through said inlet opening.

3. A consistency responsive apparatus for stock or pulp, comprising a body having an inlet opening for a constant head of stock and an outlet opening for stock the size of said openings being fixed, a supply pipe for stock leading to the inlet opening, an outlet pipe for stock communicating with the outlet opening, a continuously rotating cylinder immersed in the stock in said body, having its periphery provided with means for the passage of filtrate therethrough and the collection of solid matter thereon, at a rate depending on the consistency of the stock the level of the body of stock surrounding the cylinder being proportional to the consistency of the stock, means snugly engaging the periphery of the cylinder for receiving filtrate therefrom, means governing the flow of stock through the inlet pipe to provide a constant feed of stock to the body, and said outlet pipe having a fixed orifice.

4. A consistency responsive apparatus for thin stock comprising a source of stock at a constant head, a body having an inlet opening for stock communicating with said source; and an outlet opening for stock the size of said openings being

fixed, a cylinder in said body immersed in the stock, having its periphery formed for the passage of filtrate therethrough and the collection of solid matter thereon at a rate depending on the consistency of the stock the level of the body of stock surrounding the cylinder being proportional to the consistency of the stock, means extending across the width of the cylinder snugly engaging the periphery thereof whereby, to insure the flow of all filtrate from the interior of the cylinder without leakage and for conducting the filtrate exteriorly of the body, and a doctor carried by said means for receiving the filtrate from the cylinder for scraping the solid matter off of the cylinder, as the cylinder passes said means, and means for rotating the cylinder.

5. A consistency responsive apparatus for stock, comprising a source of stock at a constant head, a body having an inlet for stock communicating with said source and an outlet for the stock the size of the inlet and outlet being fixed, a delivery pipe for stock, communicating with the inlet pipe, a discharge pipe for stock communicating with the outlet opening, a continuously rotating cylinder in said body immersed in the stock having its periphery formed to permit the passage of filtrate therethrough and the collection of solid matter thereon at a rate depending on the consistency of the stock the level of the body of stock surrounding the cylinder being proportional to the consistency of the stock, a chamber in said body extending transversely across the cylinder in snug engagement with the periphery thereof whereby, to insure the flow of all filtrate from the interior of the cylinder without leakage, and a filtrate conduit pipe for conducting filtrate from said chamber to the discharge pipe below the outlet opening.

6. A consistency responsive apparatus for thin stock comprising a source of stock at a constant head, a body having an inlet opening for stock communicating with said source; and an outlet opening for stock, the size of said openings being fixed, a continuously rotating cylinder in said housing immersed in the stock, having its periphery formed to permit the passage of filtrate therethrough and the collection of solid matter thereon at a rate depending on the consistency of the stock the level of the body of stock surrounding the cylinder being proportional to the consistency of the stock, a chamber housing in said body extending transversely across the cylinder in snug engagement with the periphery thereof whereby, to insure the flow of all filtrate from the interior of the cylinder without leakage, means for rotating the cylinder, means in the supply pipe for regulating the flow of stock therethrough, said discharge pipe having a fixed orifice therein, and a filtrate conduit pipe for conducting filtrate from said chamber housing to the discharge pipe below said fixed orifice.

7. A consistency responsive apparatus for thin stock comprising a source of stock at a constant head, a body having an inlet opening for stock communicating with said source and a discharge opening for stock, the size of said openings being fixed, a continuously rotating cylinder in said body immersed in the stock, having its periphery formed to permit the passage of filtrate therethrough and the collection of solid matter thereon at a rate depending on the consistency of the stock the level of the body of stock surrounding the cylinder being proportional to the consistency of the stock, means for rotating the cylinder, a chamber housing in said body extending trans-

versely across the cylinder in snug engagement with the periphery thereof whereby, to insure the flow of all filtrate from the interior of the cylinder without leakage, a filtrate conduit pipe for conducting filtrate from said chamber housing and exteriorly of the body, an annular flange carried by one side wall of the body engaging one end of the cylinder, said mentioned end of the cylinder having openings therein, and a by-pass pipe extending through the mentioned side wall of the body and communicating with the body interiorly of the flange, said by-pass pipe having communication with the filtrate conduit pipe.
